(57) **CLAIM**

The ornamental design for a cosmetic brush, as shown and described.

DESCRIPTION

2. Folding cosmetic brush

2.1 : Front

2.2 : Back

2.3 : Left

2.4 : Right

2.5 : Bottom

2.6 : Top

2.7 : Cross-sectional view cut at the center of the front view

2.8 : Cross sectional view cut at center of the top view

2.9 : Cross sectional view cut horizontally of the front view

2.10 : Perspective view seen from the front side

2.11 : Perspective view seen from the back side

2.12 : Front view in a folding state

2.13 : Back view in folding state

2.14 : Left view in a folding state

2.15 : Right view in a folding state

2.16 : Top view in a folding state

2.17 : Bottom view in a folding state

2.18 : Cross sectional view in a folding state

2.19 : Perspective view seen from the back side in a folding state

2.20 : Perspective view seen from the front side in a folding state

The product is a brush used to put on makeup; As shown in the reproductions, the shape of this product is changeable from the folding state [2.12] through [2.20] to the extended state [2.1] through [2.11]; The point of respective designs is shape of product; The point of the respective designs is expressed in view [2.20].

1 Claim, 20 Drawing Sheets
